One or more rotors of an impact comminutor are mounted within a housing. A hydraulic cylinder and piston unit is laterally offset from the axis of the rotor, or the axes of adjacent rotors, being pivotably mounted on a wall of the housing. The free end of the unit can be releasably engaged with a respective rotor or a plate mounted fixedly on the shaft of the rotor and provided with circumferentially spaced apertures for connecting purposes. Thus, operation of the cylinder and piston unit serves to displace the rotor angularly to a desired angular position.

IMPACT COMMINUTOR

BACKGROUND OF THE INVENTION

The present invention relates generally to comminutors, and more particularly to impact comminutors.

Impact comminutors are already known in a variety of different types and constructions. Some of these are in form of hammer mills and others are in form of impact comminutors, but they all use one or more rotors which turn in a housing and with which the material -- rocks and the like -- comes in contact to be impacted and crushed.

All such rotors are provided with beating instrumentalities, in the case of hammer mills with hammers, and in the case of impact comminutors with beater bars. Of course, over a period of time, these instrumentalities will wear or become damaged, and must then be removed for repair or replacement. In order to do this, it is necessary to impart to the rotor such movement as to place the rotor into a requisite angular position so that the lateral access openings provided in the housing will afford access to the impacting instrumentalities which are to be removed or replaced. Many comminutors of the type here under discussion are rather large, and their rotors are correspondingly heavy and difficult to turn. This means that manual displacement of the rotor to the desired angular position is frequently impossible, whereas the drive which normally turns the rotor during operation of the apparatus, also cannot be used because it will turn the rotor much too fast and does not permit positioning of the rotor in a desired angular position.

In addition, there is a further problem with this type of comminutors, namely once the rotor has been moved to the desired angular position, it is essential that it be arrested in this position to prevent it from turning a circumstance which will necessarily occur as a result of changes in the center of gravity as certain of the beating instrumentalities are removed for replacement. Evidently, such undesired and unintentional turning can lead to accidents of the personnel involved in working on the apparatus.

The problem has been recognized before and the art has, in fact, made attempts to solve the problem. These attempts however, are without exception relatively complicated and expensive in their conception and construction, and in operation require a high degree of precision at small play in order to assure that the rotor will in fact be fixedly arrested at the desired angular position. Thus, the known arrangements which usually utilize a gearing construction, must be dimensioned rather large which is an additional disadvantage because it requires valuable space which usually cannot be provided without increasing the overall dimensions of the comminutor, thus taking up floor space which is at a premium at most installations.

SUMMARY OF THE INVENTION

It is, accordingly, an object of the present invention to provide an improved impact comminutor which is not possessed of the above-mentioned disadvantages.

More particularly it is an object of the present invention to provide, in an impact comminutor, a construction in which the rotor can be readily positioned in a desired angular position and can be arrested in the once-assumed angular position.

A concomitant object of the invention is to provide such an arrangement which is very simple in its construction and operation, and which requires very little space.

Still a further object of the present invention is to provide such an arrangement which is highly economical in its construction and can, according to an embodiment of the invention, be used with two adjacent rotors in cases where the comminutor has two or more rotors.

In pursuance of the above objects and of others which will become apparent hereafter, one feature of the invention resides in an impact comminutor having a combination of wall means defining an interior chamber and rotor means mounted for rotation in this chamber. A cylinder and piston unit has a first end and a second end, mounting means being provided which pivotally mounts the unit on the wall means laterally offset from the rotor means. Releasable connecting means is provided for releasably connecting said second end of the unit with the rotor means in order to move the latter to a desired angular position in response to operation of the unit.

Thus, it is a simple matter of operating the cylinder and piston unit which advantageously but not necessarily is of the hydraulic type, to thereby turn the rotor to a desired angular position after the second end of the unit has been connected with the rotor. Thereupon the rotor is arrested in the desired angular position by arresting means which is provided according to a further concept of the invention.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

BRIEF DESCRIPTION OF THE DRAWING

The single FIGURE is a somewhat diagrammatic end-elevational view of a comminutor embodying the invention.

DESCRIPTION OF THE PREFERRED EMBODIMENTS

The invention has been illustrated by way of example in an impact comminutor of the type provided on its rotor with a plurality of beater bars which extend longitudinally of the axis of rotation of the rotor. It is, however, equally applicable to any other type of comminutor having one or more rotors as was already pointed out. In addition, it should be noted that the invention has been illustrated in the form of an impact comminutor having two adjacent rotors; the invention is, of course, applicable also to impact comminutors having only a single rotor or to impact comminutors having more than two rotors.

With this in mind it is pointed out that the drawing shows an impact comminutor having a housing 1 bounded by wall means 1'. Mounted for rotation in the housing 1, that is in the interior chamber thereof, are two diagrammatically illustrated rotors 10, which are shown in chain lines and provided on their peripheries with beater bars 10a. These rotors turn about axes 4 which in this embodiment extend in parallelism with

one another and are transversely spaced from one another.

It should be noted that the illustration is such as to show the end wall of the housing 1, provided with a pair of access openings 1'' through which access is to be had to the beater bars 10a. Consequently, the beater bars 10a, which are located in registry with the respective openings 1'' are shown in full lines, whereas the other and the remainder of the respective rotor 10 are shown in chain lines.

Each of the rotors 10 is provided with a disc-shaped member 3 which is mounted outside the chamber on its respective shaft constituting the axis of rotation, with the members 3 being fixed with the shaft and rotatable therewith. Each of the members 3 is provided with a plurality (here four) of openings 5, which in the illustrated embodiment are equi-angularly spaced. Of course, more or fewer than these openings 5 could be provided and they need not be equi-angularly spaced.

Mounted on one of the walls 1' of the housing 1 is a cylinder and piston unit 2 which shall be assumed to be hydraulically operated but it could also be operated otherwise. The unit 2 has two opposite ends a first one of which is connected by suitable mounting means 1a (a pivot or the like) to the wall of the housing 1 so that in its normal rest position in which it is not used, the unit 2 will depend under the influence of gravity from the pivot provided by the mounting means 1a in the chain line position. The opposite or second end of the unit 2 is provided with an eye or aperture 6.

When the respective rotors — with which the unit 2 can selectively be connected — are to be turned to a desired angular position the unit 2 is connected with the respective member 3 by for instance passing a pin or other connecting means 6a through one of the openings 5 and through the eye 6 of the unit 2. Thereafter the unit 2 is operated in a sense extending or retracting its piston rod whereby the rotor coupled with it can be turned either in clockwise or in counterclockwise direction until the beater bar 10a or analogous element which is to be inspected or engaged through the respective opening 1' will be juxtaposed with the latter.

It goes without saying that instead of providing the separate disc-shaped members 3, the openings 5 could also be provided directly on the respective rotor 10, and that instead of the openings 5 (either on the member 3 or on the rotor itself) other connecting means could be provided for instance projections or the like.

In operation, the unit 2 is pivoted about the point 1a towards that one of the two rotors with which it is to cooperate, in the illustrated embodiment to the left-hand one, until it is in the full line position shown. Because the point 1a is located equi-distantly between the axis 4, the unit 2 will normally depend between the two members 3 out of contact with both until such time as it is to be used.

The unit 2 may be operated, for instance, by means of a foot-actuated pump 9, with which it is connected in suitable manner via the illustrated (no reference numerals) hydraulic lines.

Of course, the mounting of the unit 2 can be reversed and the eye 6 can be connected to the wall 1' by the mounting means 1a, whereas the other end portion can be releasably connected with the respective rotors.

Once the rotor or rotors have been moved to the desired angular position in response to operation of the unit 2, they should be restful in this position until such

time as they are to be released again for subsequent rotation. This is accomplished by providing an arresting device 7 having, in the illustrated embodiment, at least one or two transversely spaced lugs 7; the single lug 7 is formed with an opening 8 or, if two of the lugs are provided transversely spaced from one another, there are two openings 8 provided which are in registry with one another. The lugs 7 are so located that they overlap the members 3 as illustrated, and of course, if there are

two of the lugs 7 provided then the respective disc member 3 will be located between them. The openings 8 are so located that the openings 5 of the associated disc-member 3 can be placed into registry with the respective opening or openings 8. Thus, when the rotor 10 has assumed the desired angular position, with the aid of the unit 2, and when one of the openings 5 of its disc member 3 is in registry with the opening or openings 8, then arresting can simply be carried out by inserting a pin or the like through the registering openings 5 and 8, thereby preventing the rotor 10 from turning and retaining it in the selected angular position until such time that the ball or pin is withdrawn. Disc-shaped member 3 may be in the form of a single disc or two parallel discs, the latter thus aligning the pins or other connecting means 6a with opening 8 in lug or lugs 7 or with eye 6 more accurately.

For the sake of completeness, the cooperating impact units 10b have also been illustrated which cooperate with the rotors 10 and on which material flung by the 30 rotors and flung against the units 10b, will crash to fall back on the rotors and obtain additional impacts in the sense communiting it. These units 10b have been shown only for orientation and do not form part of the present invention, being entirely conventional in the impact-rebound type of comminutor.

It will be appreciated that the present invention achieves the afore-mentioned objects and does so in a simple and reliable as well as expeditious manner. The 40 space requirements of the novel arrangement are very small, and on the other hand, manual turning of the rotor is no longer necessary. Then again, the rotor can be reliably and for any desired period of time arrested in the selected angular position, thereby avoiding the possibility of accidental turning and danger to an operator.

Although as pointed out above, the invention is applicable to a comminutor having only a single rotor, it will be appreciated that it is particularly advantageous 50 where a comminutor has two or more rotors, because a single unit 2 can serve two adjacent ones of the rotors. Thus, the economy of constructing the arrangement according to the present invention is also significantly improved over what is known from the prior art.

It will be understood that each of the elements described above, or two or more together, may also find a useful application in other types of constructions differing from the types described above.

While the invention has been illustrated and described as embodied in an impact comminutor, it is not intended to be limited to the details shown since various modifications and structural changes may be made without departing in any way from the spirit of the present invention.

Without further analysis, the foregoing will so fully reveal the gist of the present invention that others can, by applying current knowledge, readily adapt it for various applications without omitting features, that from

the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims.

I claim:

1. In an impact comminutor, in combination, wall means defining an interior chamber and having an outer side; rotor means mounted for rotation in said chamber and including a shaft having a shaft portion located at said outer side; a disk member fixedly mounted on said shaft portion and provided with a plurality of connecting portions which are spaced about the circumference of said shaft; a cylinder and piston unit having a first end and a second end; mounting means cooperating with said first end and pivotally mounting said unit on said wall means laterally spaced from said shaft and disk member; and connecting means for releasably connecting said second end of said unit with respective ones of said connecting portions when it is desired to change the angular position of said rotor means, so as to move the latter to a desired angular position in response to operation of said unit and prior to release of said connecting means from the respective connecting portion.

2. In an impact comminutor as defined in claim 1, wherein said unit is a hydraulic cylinder-and-piston unit.

3. In an impact comminutor, in combination, wall means defining an interior chamber; rotor means mounted for rotation in said chamber and comprising a rotary shaft; a cylinder and piston unit having a first end and a second end; mounting means cooperating with said first end and pivotally mounting said unit in said wall means laterally offset from said rotor means; and releasable connecting means for releasably connecting said second end of said unit with said rotor means, including a disk member fixed with said rotor means so as to rotate with said shaft and being provided with a plurality of angularly spaced openings, and a connector engageable with said second end and in a respective one of said openings so as to move said rotor

means to a desired angular position in response to operation of said unit.

4. In an impact comminutor as defined in claim 3, wherein said openings are equi-angularly spaced.

5. In an impact comminutor as defined in claim 3; further comprising an arresting element on said wall means, and including an arresting member operative for engagement with said arresting element and in a respective one of said openings for arresting said rotor means in the respective angular position.

10 6. In an impact comminutor as defined in claim 3, wherein said second end is provided with an eye, and wherein said connector is a pin insertable into said eye and respective ones of said openings.

15 7. In an impact comminutor, in combination wall means defining an interior chamber; rotor means mounted for rotation in said chamber and including a pair of rotors rotatable about transversely spaced and substantially parallel axes; a cylinder and piston unit having a first end and a second end; mounting means cooperating with said first end and mounting said unit on said wall means substantially midway between said axes for pivotal displacement from a normal substantially vertical position to respective lateral positions inclined towards the respective rotor axis from said normal position; and connecting means for releasably connecting said second end of said unit with a respective selected one of said rotors so as to move the latter to a desired angular position in response to operation of said unit.

20 30 35 8. In an impact comminutor as defined in claim 1, wherein said mounting means mounts said first end of said unit on said wall means for movement about a pivot axis located at a level higher than the level at which said disk member is located.

9. In an impact comminutor as defined in claim 1, wherein said second end comprises a portion configured as an eye, and said connecting portions are holes in said disk members; and wherein said connecting means comprises a pin which can be inserted into and withdrawn from said eye and selected ones of said holes.
